EDGE GRINDING MACHINE

Joseph P. Crowley, Toledo, Ohio, assignor to
Libbey-Owens-Ford Glass Company, Toledo,
Ohio, a corporation of Ohio

Application May 17, 1934, Serial No. 726,055

19 Claims. (Cl. 51—96)

The present invention relates broadly to improvements in grinding machines generally and more particularly to a machine for rounding end/or finishing the edges of sheets or plates of glass and the like.

An important object of this invention resides in the provision of a grinding machine of relatively simplified and inexpensive construction primarily designed for use in grinding the curved edges or corners of sheets or plates of glass which are to be employed as door or window lights in automotive vehicles, although it is of course in no way restricted to such use.

Another object of the invention is the provision of such a grinding machine of the above character which will round and finish the curved edges or corners of the glass sheets or plates rapidly, accurately, and economically, and with a minimum amount of effort and attention on the part of the operator, whereby uniformly rounded edges with well finished surfaces may be secured.

A further object of the invention is the provision of such a grinding machine of the above character capable of grinding curved edges of different contours and embodying generally a rotary grinding wheel, means mounted above said wheel for supporting a plurality of glass sheets to be treated, and means for rocking said supporting means to move the glass sheets backward and forward with the curved edges thereof to be ground over and in engagement with the grinding wheel, said sheet supporting means being mounted for free vertical guided movement during the rocking thereof and depending upon the contour or curvature of the edges being surfaced.

Other objects and advantages of the invention will become more apparent during the course of the following description when taken in connection with the accompanying drawings.

In the drawings wherein like numerals are employed to designate like parts throughout the same,

Fig. 1 is a side elevation of an installation including two spaced grinding machines constructed in accordance with the present invention and a conventional polishing machine arranged therebetween.

Fig. 2 is a vertical section through one of the grinding machines taken substantially on line 2—2 of Fig. 1.

Fig. 3 is a detail section taken substantially on line 3—3 of Fig. 2.

Fig. 4 is a perspective view of the upper portion of the grinding machine showing particularly the

means for supporting the glass sheets to be treated.

Fig. 5 is a detail section taken substantially on line 5—5 of Fig. 2.

Fig. 6 is a section taken substantially on line 6—6 of Fig. 4.

Fig. 7 is a view of one of the side members of the glass supporting means.

Figs. 8, 9 and 10 are side views showing different positions assumed by the sheet supporting means and the glass sheets during the grinding operation, and

Fig. 11 is a side elevation of the sheet supporting means modified to receive glass sheets having a different contour from those disclosed in Figs. 1 and 8 to 10.

Referring now to the drawings and particularly to Fig. 1, there is illustrated one type of factory installation embodying two grinding machines A and B constructed in accordance with the present invention and a conventional polishing machine C. The grinding machines are disposed opposite one another in spaced relation and the polishing machine is arranged therebetween. The edges of the glass sheets 15, after being ground upon the grinding machines A and B, are adapted to be polished upon the polishing machine C. With this particular installation, a single polishing machine can handle the glass ground upon both grinding machines inasmuch as it takes longer to grind than to polish. Thus, while one of the grinding machines is in operation, an operator can be removing the ground sheets from the other grinding machine and effecting the polishing or finishing of the edges of said sheets upon the polishing machine. The polishing machine includes a polishing wheel 16 rotatable about a substantially horizontal axis within a receptacle 17 adapted to contain a suitable polishing material within which the lower portion of the said polishing wheel rotates as is well known in the art. The glass sheet, shown in broken lines and designated 15a, is adapted to be manually moved by the operator back and forth over the polishing wheel.

In order to facilitate the transfer of the glass sheets from the grinding machines A and B to the polishing machine C, there may be arranged at opposite sides of the said polishing machine a runway D comprising a series of horizontally aligned rotatable rolls 18. The operator can then slide the glass sheets from the grinding machines along the runway to the polishing machine. The installation shown in Fig. 1 will permit of the grinding and polishing of a maximum number of

sheets rapidly and conveniently and with a minimum amount of handling. If desired, however, two polishing machines can be employed, with each of the polishing machines being adapted 5 to receive the glass sheets from one of said grinding machines.

The grinding machines A and B are adapted to produce what is termed in the art as a "pencil edge" upon the glass sheets. The term "pencil edge" is used to designate an edge which is rounded transversely of the sheet to remove all sharp or square corners. Inasmuch as the two 10 grinding machines are of exactly the same construction, a detailed description of only one will 15 be given. Thus, upon reference particularly to Fig. 2, each grinding machine includes a base 19 which is adapted to support the rotary grinding wheel 20 and the motor 21 for driving the same, said motor being mounted upon the top 20 of said base and the grinding wheel being arranged to one side thereof.

The grinding wheel 20 is keyed to one end of a horizontal shaft 22 and is provided in its periphery with a plurality of circumferential grooves 23 within which the edges of the glass sheets or plates 15 to be ground are adapted to be received as will be more clearly hereinafter apparent. The shaft 22 is rotatably supported in spaced 25 bearings 24 and 25 carried by the base 19, said 30 shaft projecting rearwardly beyond said base and being journaled at its outer end in a bearing 26 carried by a gear case 27 suitably secured to the said base. Keyed to the shaft 22 within gear case 27 is a relatively large gear 28 meshing with 35 a relatively smaller gear 29 fixed to the shaft 30 of motor 21, said shaft being preferably journaled in a bearing 31 also carried by gear case 27. Upon operation of the motor 21, it will be readily 40 apparent that the shaft 22 will be driven through the intermeshing gears 28 and 29 to effect the positive rotation of the grinding wheel.

Arranged at the front of the base 19 is a receptacle 32 within which the grinding wheel 20 is received, said receptacle being adapted to contain 45 a suitable abrasive material within which the lower portion of the said wheel is immersed in a manner well known in the art. The top of the receptacle 32 is provided with a slot 33 through which the upper portion of the grinding 50 wheel projects. The receptacle is also preferably provided with a door 34 to permit access thereto and with a drain outlet 35 at one corner thereof.

The base 19 is slidably associated with the receptacle 32 so that it can be moved vertically 55 relative thereto to either raise or lower the grinding wheel. To this end, the rear vertical wall 36 of the receptacle is formed with a vertical undercut channel or way 37 (Fig. 3) within which the slide 38 formed on or carried by the base 19 is received. The rear wall of said receptacle is also 60 provided with a vertical slot 39 through which projects the annular portion 40 of the base 19 within which bearing 24 is mounted.

The base 19 is supported upon a screw 41 65 threaded at its lower end within a vertical cylinder or sleeve 42 carried upon the base portion 43 of receptacle 32. The base 19 is formed with a recess 44, and keyed to the upper end of screw 41 within said recess is a relatively large gear 45 meshing with a relatively smaller gear 46 keyed to the lower end of a vertical shaft 47 which passes downwardly through the said base. Extending transversely through the upper end of the 70 shaft 47 is a rod 48 constituting a handle which may be grasped by the operator to facilitate the

turning of shaft 47. From the above, it will be seen that when it is desired to either raise or lower the base 19 and consequently the grinding wheel 20, it is simply necessary for the operator to grasp the handle 48 and turn the shaft 47 5 in the desired direction. The rotation of gear 46 will serve to effect a corresponding rotation of gear 45 and upon rotation of this latter gear, the screw 41 will be threaded upwardly or downwardly within the sleeve 42 to effect either the 10 raising or the lowering of the base and grinding wheel.

The means for supporting the glass sheets 15 to be ground comprises a carrier or holder designated in its entirety by the numeral 49, said 15 holder being mounted above the grinding wheel 20 for free vertical and rocking movement relative thereto as will be more fully hereinafter described. The work holder 49 comprises a pair of spaced vertical side members 50 and 51 between 20 which a plurality of the glass sheets 15 are adapted to be received so that the edges thereof may be ground simultaneously, said sheets being disposed on edge in a vertical position and the said side members 50 and 51 being so shaped that 25 upon rocking of the work holder, the curved edges or corners 52 of the glass sheets to be treated will be moved backward and forward over and in engagement with the grinding wheel. It will be noted that the side member 51 is relatively 30 smaller than side member 50.

Arranged transversely between and carried by the side members 50 and 51 of work holder 49 are the two rollers 53 and 54 respectively, said rollers being also adapted to maintain the said side members in properly spaced relation relative to one another. Removably carried by the side member 50, adjacent the upper end thereof, are the three rollers 55, 56 and 57, while carried thereby adjacent the lower end thereof and in substantial alignment with roller 54 are rollers 58 and 59. The rolls 53 to 59 are adapted to receive the glass sheets 15 therebetween and to maintain them in proper position within the work holder during the grinding operation, the grinding of glass sheets 45 of different contours bringing into use different rollers. For instance, as shown in Figs. 1 and 8 to 10, the glass sheets 15 are maintained in position by the rollers 53, 54, 55, 57, and 58, while in Fig. 10, the glass sheets 15b, which are of a different shape, are held in place by the rollers 53, 54, 55, 56 and 58, the roller 57 having been removed. Were the sheets 15b slightly longer, they 50 would also be supported by the roller 59.

The roller 53 comprises a horizontal bolt 60 55 (Fig. 6) having its inner end extending through an inclined slot 61 in the side member 50 and being secured in place by a nut 62. The opposite or outer end of the bolt extends through a circular opening 63 in side member 51 and is formed at its outer end with a head 64. Mounted upon the bolt 60 is a metal bushing 65 carrying a sleeve 66 preferably made of relatively soft rubber. This sleeve is formed with a plurality of uniformly spaced annular flanges 67 which define therebetween a plurality of grooves 68 within which the adjacent edges of the glass sheets to be ground are adapted to be received, the grooves 68 in the roller being in registry with the grooves 23 in grinding wheel 20. Carried upon the bolt at opposite ends of the sleeve 66 are collars 69 and 70. 65

The roller 54 is of the same construction and arrangement as roller 53 and is carried by the side members 50 and 51 in the same manner, the bolt 60 thereof passing through an inclined slot 75

71 in side member 50. The slots 61 and 71 in side member 50 are provided in order to facilitate the proper positioning of the side member 51 with respect to side member 50 upon assembling of the 5 work holder.

The rollers 56, 57, 58 and 59 are also of substantially the same construction as rollers 53 and 54 with the exception that they are carried entirely by the side member 50, the bolts 60 of the 10 said rollers passing through slots 72, 73, 74, 75 and 76 respectively (Fig. 7) in the said side member and being secured in place by nuts threaded upon the said bolts outwardly thereof. The slots 72 to 76 are provided to permit the rollers 55 to 59 15 respectively to be adjusted with respect to one another in a manner to permit of the grinding of glass sheets of different sizes. Likewise, any one of the rollers 55 to 59 can be readily and conveniently removed should it be found necessary in 20 order to accommodate a particular shape or size of sheet. For instance, a glass sheet 15 of one particular shape and size is illustrated in Figs. 1 and 8 to 10, and in this case the upper substantially horizontal straight edge *a* thereof engages 25 the rollers 55 and 57; the curved bottom edge *b* thereof the rollers 54 and 58; and the substantially vertical straight edge *c* the roller 53. The bottom edge *b* and side edge *c* are connected by the corner or curved edge 52 to be ground. On 30 the other hand, in Fig. 10, and because of the particular shape of the glass sheet 15b, the roller 57 has been removed and the upper edge *d* of the said sheet engages roller 56; the inner curved edge *e* the rollers 53 and 55; and the bottom edge 35 *f* the rollers 54 and 58. The curved edge *e* and bottom edge *f* are connected by the curved edge 52 to be ground. The rollers 55 to 59 are of course each provided with a plurality of grooves 40 which are in alignment with the grooves in rollers 53 and 54 and likewise in registry with the grooves in the grinding wheel.

Mounted upon the top of the receptacle 32 at opposite sides thereof is a pair of opposed guide brackets 77 and 78 respectively, each being 45 formed with a vertical guideway 79 within which is slidably mounted a guide block 80 for free vertical movement. Secured to the outer surfaces of the side members 50 and 51 of the work holder and extending diagonally thereof are plates 81 50 and 82 respectively. Carried by each of the side members 50 and 51 of the work holder and passing transversely through the respective plate 81 or 82 (Fig. 5) is a trunnion 83 riveted to the said side member as at 84. Each trunnion projects 55 outwardly beyond the respective plate 81 or 82 and is loosely received within the respective guide block 80 so that it can turn freely relative thereto. With this construction, it will be readily apparent that the trunnions 83 define a horizontal axis 60 about which the work holder 49 is adapted to be rocked to move the corners or curved edges of the glass sheets to be ground over and in engagement with the grinding wheel and that during such rocking movement the said work holder will be 65 permitted to move freely vertically, depending upon the curvature of the edges being treated.

Carried by the plates 81 and 82 are the horizontally aligned stub shafts 85 and 86 to which are pivotally connected the inner ends of the 70 substantially horizontal parallel connecting arms 87 and 88 respectively pivotally connected at their outer ends to the horizontal pins 89 and 90 carried at the inner ends of the substantially V-shaped crank levers 91 and 92 respectively, said 75 crank levers being mounted intermediate their

ends upon a horizontal shaft 93 journaled in the horizontal bearing 94 formed at the upper end of a bracket 95 secured to the receptacle 32 by bolts or other suitable fastening elements 96.

Carried at the opposite or outer ends of the V-shaped levers 91 and 92 are pins 97 and 98 to which are pivotally connected the upper ends of the substantially vertical pitman rods 99 and 100, each of said rods being also pivotally connected at its lower end to a crank 101 keyed to a horizontal shaft 102, said shaft being driven from a motor 103 through a suitable drive 104 and reduction gearing located in the housing 105. Upon rotation of the shaft 102, the pitman rods 99 and 100 will be given a substantially vertical up and down motion to effect the rocking of the V-shaped crank levers 91 and 92 first in one direction and then the other to impart a substantially horizontal forward and backward motion to the connecting rods 87 and 88. The reciprocation of the connecting rods will cause a rocking of the work holder 49 as the trunnions 83 turn freely within guide blocks 80, thereby causing the glass sheets 15 to be moved backward and forward, with the curved edges 52 thereof to be ground over and in engagement with the grinding wheel 20. Simultaneously with its rocking movement, the said work holder will be permitted to move freely vertically as a result of the guide block 80 operating within guideways 79.

In the operation of the machine described above and when it is desired to grind the curved edges or corners 52 of a plurality of sheets of glass 15, the work holder 49 is first moved to the position illustrated in Fig. 8, at which time the 35 pitman rods 99 and 100 will be at substantially the limit of their upward movement and the connecting rods 87 and 88 in their extreme forward position. The glass sheets to be ground are then inserted horizontally into the outer open end of the work holder between the upper rollers 55 and 57 and the lower rollers 54 and 58, the upper edges *a* of the said sheets being received within the grooves in the first-mentioned pair of rollers, while the bottom edges *b* thereof are received 45 within the grooves of the second-mentioned pair of rollers. The glass sheets are moved inwardly until the inner edges *c* thereof abut and are received within the grooves of roller 53.

After the glass sheets have been thus properly 50 positioned, the motor 103 is placed in operation to rotate shaft 102 and draw the pitmen 99 and 100 downwardly, this movement causing the crank levers 91 and 92 to be rocked in a counterclockwise direction to retract the connecting rods 55 87 and 88. This movement of the connecting rods will cause the work holder 49 to be also rocked in a counterclockwise direction and during the turning of the said work holder, the curved edges 52 of the glass sheets will of course 60 be moved over and in engagement with the grinding wheel 20, being received within the grooves 23 thereof. The work holder is turned approximately 90° and at the limit of its backward movement will assume substantially the position illustrated in Fig. 10, at which time the glass sheets 65 will be supported upon the roller 53.

When the work holder 49 is in this position, the crank 101 has completed approximately one-half a revolution so that upon continued turning of the said crank, the pitmen 99 and 100 will be 70 started upwardly, thereby causing the crank levers 91 and 92 to be rocked in a clockwise direction to effect forward movement of the connecting rods 87 and 88. This movement of the con- 75

necting rods will in turn cause the work holder to be rocked also in a clockwise direction to return it to its starting position shown in Fig. 8. During the rocking of the work holder, the grinding wheel 20 is also being positively driven from motor 21.

- It will of course be readily apparent that upon rocking of the work holder 49, the said holder will be permitted to simultaneously move freely vertically, depending upon the curvature of the sheet edges being ground, said work holder being guided in a definite path during its vertical movements by means of the guide blocks 80 operating in the guideways 79 of guide brackets 77 and 78. 10
- 15 Due to the above construction, curved edges of different contours can be readily and conveniently ground upon the machine and without necessitating any special adjustment to take care of each particular curve, except as regards the adjustment of the rollers relative to one another to take care of different size sheets. This renders the machine capable of a wide use and permits the simultaneous grinding of a plurality of sheets of glass rapidly, accurately, and economically, 20 and with a minimum effort and attention on the part of the operator. While the machine has been referred to above as a grinding machine and also while it is primarily designed for this purpose, yet it may be readily adapted for polishing 25 the curved edges of the glass sheets by the substitution of a suitable polishing wheel for the grinding wheel 20.

It is desirable, in the operation of the machine, to effect a slight raising of the glass sheets 30 at the completion of the grinding operation to lift the said sheets out of contact with the grinding wheel in order to prevent "burning" of the edges being ground. To this end, there is carried upon the top of the receptacle 32, adjacent the forward end thereof, two spaced blocks 106 and 107 adapted to be engaged by the side members 50 and 51 respectively of the work holder at the completion of the grinding cycle to effect a slight 35 tilting of the said holder sufficient to lift the glass sheets out of contact with the grinding wheel (Fig. 8). Also, upon loading of the work holder, preparatory to the grinding operation, the said holder is adapted to be in this position so that the curved edges 52 of the glass sheets 40 will not contact with the grinding wheel as the said sheets are being placed in position. When the motor 103 is then placed in operation to rock the work holder, the curved edges of the glass sheets will be gradually lowered to engage the 45 grinding wheel as illustrated in Fig. 9.

Ordinarily, it will be found that one backward and forward rocking movement of the work holder is sufficient to effect the desired grinding of the glass sheets. Therefore, the present invention 50 contemplates the provision of means for automatically shutting off the motor 103 and stopping the rocking movement of the work holder at the completion of the grinding operation. For the accomplishment of this object, there is carried by the base 19 a limit switch 108 (Fig. 2) 55 connected in series with and adapted to control the operation of motor 103, said switch being provided with a control arm 109 having a roller 110 at its outer end. Secured to the side member 50 of the work holder for cooperation with the switch is a trip member 111 (Figs. 2, 8 and 10). In practice, after the work holder has been rocked in a counterclockwise direction to the position illustrated in Fig. 10 and then returned to its 60 starting position shown in Fig. 8 to complete the

grinding cycle, the trip member 111 engaging roller 110 will force the control arm 109 downwardly to open switch 108, thereby breaking the circuit through motor 103 and stopping the movement of the work holder. The trip member 111, however, is not adapted to actuate switch 108 until after the side members 50 and 51 of the work holder engaging blocks 106 and 107 have caused the glass sheets to be lifted out of contact with the grinding wheel as explained above. 10

It is to be understood that the form of the invention herewith shown and described is to be taken as the preferred embodiment of the same, and that various changes in the shape, size and arrangement of parts may be resorted to without departing from the spirit of the invention or the scope of the subjoined claims. 15

I claim:

1. In a machine for grinding the curved edge of a glass sheet or plate, a rotary grinding wheel 20 positioned to rotate about a substantially horizontal axis, means mounted above said grinding wheel for supporting the glass sheet to be ground on edge in a substantially vertical position, means for rocking said supporting means to move the 25 curved edge of the sheet to be ground over and in engagement with the grinding wheel, said sheet supporting means being mounted for free vertical movement during the rocking thereof, and means for guiding the said supporting means in its vertical movements. 30

2. In a machine for grinding the curved edge of a glass sheet or plate, a rotary grinding wheel positioned to rotate about a substantially horizontal axis, means mounted above said grinding wheel 35 for supporting the glass sheet to be ground on edge in a substantially vertical position, means for mounting said sheet supporting means for free vertical and rocking movement, means for 40 rocking the supporting means, and means for guiding the said supporting means in a definite path during vertical movement thereof. 45

3. In a machine for grinding the curved edge of a glass sheet or plate, a rotary grinding wheel positioned to rotate about a substantially horizontal axis, means mounted above said grinding wheel 50 for supporting the glass sheet to be ground on edge in a substantially vertical position, means for pivotally mounting said sheet supporting means, means for rocking the supporting means about its pivot to move the curved edge of the sheet to be ground over and in engagement with the grinding wheel, and means for 55 guidingly supporting the said sheet supporting means for free vertical movement during the rocking thereof. 60

4. In a machine for simultaneously grinding the curved edges of a plurality of glass sheets or plates, a rotary grinding wheel positioned to rotate about a substantially horizontal axis, a work holder arranged above said wheel and adapted to support the glass sheets to be ground on edge in a substantially vertical position, said work holder including spaced vertical side members between which said sheets are received and means carried by and arranged between said side members for maintaining the said sheets in position during grinding, means connected with the work holder for rocking the same about a horizontal axis to move the curved edges of the sheets over and in engagement with the grinding wheel, said work holder being mounted for free vertical movement during the rocking thereof, and means for guiding the said work holder in its vertical movements. 70

5. In a machine for simultaneously grinding the 75

- curved edges of a plurality of glass sheets or plates, a rotary grinding wheel positioned to rotate about a substantially horizontal axis, a work holder arranged above said wheel and adapted to support 5 the glass sheets to be ground on edge in a substantially vertical position, said work holder including spaced vertical side members between which said sheets are received and means carried by and arranged between said side members for 10 maintaining the said sheets in position during grinding, means for mounting the work holder for free vertical and rocking movement, means connected with said work holder for rocking the same, and means for guiding the said work holder 15 in a definite path during vertical movement thereof.
6. In a machine for simultaneously grinding the curved edges of a plurality of glass sheets or plates, a rotary grinding wheel positioned to 20 rotate about a substantially horizontal axis, a work holder arranged above said wheel and adapted to support the glass sheets to be ground on edge in a substantially vertical position, said work holder including spaced vertical side members between which said sheets are received and means carried by and arranged between said side members for maintaining the said sheets in position during grinding, means for pivotally 25 mounting the work holder, means connected with 30 said work holder for rocking the same about its pivot to move the curved edges of the sheets over and in engagement with the grinding wheel, and means for guidingly supporting the said work holder for free vertical movement during the 35 rocking thereof.
7. In a machine for simultaneously grinding the curved edges of a plurality of glass sheets or plates, a rotary grinding wheel positioned to rotate about a substantially horizontal axis, a work 40 holder arranged above said wheel and adapted to support the glass sheets to be ground on edge in a substantially vertical position, said work holder including spaced vertical side members between which said sheets are received and means carried by and arranged between said side members for maintaining the said sheets in position during grinding, fixed guide brackets mounted at opposite sides of the work holder and having vertical guideways therein, means carried by the 45 side members of said work holder and slidably received within said guideways, said last-mentioned means being constructed to cause rocking movement of the work holder relative to said guide brackets, and means for rocking the said 50 work holder to move the curved edges of the sheets over and in engagement with the grinding wheel.
8. In a machine for simultaneously grinding the curved edges of a plurality of glass sheets or 55 plates, a rotary grinding wheel positioned to rotate about a substantially horizontal axis, a work holder arranged above said wheel and adapted to support the glass sheets to be ground on edge in a substantially vertical position, said work holder including spaced vertical side members between which said sheets are received and means carried by and arranged between said side members for maintaining the said sheets in position during grinding, fixed guide brackets 60 mounted at opposite sides of the work holder and having vertical guideways therein, blocks slidably mounted in said guideways, horizontal trunnions carried by the side members of the work holder and loosely received within said blocks 65 70 75 defining a horizontal axis about which the said work holder is adapted to be rocked, and means connected with said work holder for rocking the same about such axis to move the curved edges of the sheets over and in engagement with the grinding wheel.
9. In a machine for simultaneously grinding the curved edges of a plurality of glass sheets or plates, a rotary grinding wheel positioned to rotate about a substantially horizontal axis and having a plurality of grooves formed in the periphery thereof, means for supporting the glass sheets to be ground on edge in a substantially vertical position including a holder arranged above said grinding wheel and comprising spaced vertical side members between which said sheets are received and a plurality of horizontal rollers carried by and arranged between said side members for maintaining the glass sheets in position during grinding, said rollers being provided with grooves in registry with the grooves in the grinding wheel and within which the edges of the glass sheets are adapted to be received, means for rocking said work holder to move the curved edges of the glass sheets over and in engagement with the grinding wheel, said work holder being mounted for free vertical movement during the rocking thereof, and means for guiding the said holder in its vertical movements.
10. In a machine for simultaneously grinding the curved edges of a plurality of glass sheets or 30 plates, a rotary grinding wheel positioned to rotate about a substantially horizontal axis and having a plurality of grooves formed in the periphery thereof, means for supporting the glass sheets to be ground on edge in a substantially 35 vertical position including a holder arranged above said grinding wheel and comprising spaced vertical side members between which said sheets are received and a plurality of horizontal rollers carried by and arranged between said side members for maintaining the glass sheets in position during grinding, said rollers being provided with grooves in registry with the grooves in the grinding wheel and within which the edges of the glass sheets are adapted to be received, means for 40 mounting said work holder for free vertical and rocking movement, means for rocking the work holder, and means for guiding the said work holder in a definite path during vertical movement thereof.
11. In a machine for simultaneously grinding the curved edges of a plurality of glass sheets or plates, a rotary grinding wheel positioned to rotate about a substantially horizontal axis and having a plurality of grooves formed in the periphery thereof, means for supporting the glass sheets to be ground on edge in a substantially 45 vertical position including a holder arranged above said grinding wheel and comprising spaced vertical side members between which said sheets are received and a plurality of horizontal rollers carried by and arranged between said side members for maintaining the glass sheets in position during grinding, said rollers being provided with grooves in registry with the grooves in the grinding wheel and within which the edges of the glass sheets are adapted to be received, means for 50 pivotally mounting said work holder, means for rocking the work holder about its pivot to move the curved edges of the sheets over and in engagement with the grinding wheel, and means for guidingly supporting the said work holder for free vertical movement during the 55 rocking thereof.
12. In a machine for simultaneously grinding 70 75 80 85 90 95 100

the curved edges of a plurality of glass sheets or plates, a rotary grinding wheel positioned to rotate about a substantially horizontal axis and having a plurality of grooves formed in the periphery thereof, means for supporting the glass sheets to be ground on edge in a substantially vertical position including a holder arranged above said grinding wheel and comprising spaced vertical side members between which said sheets are received and a plurality of horizontal rollers carried by and arranged between said side members for maintaining the glass sheets in position during grinding, said rollers being provided with grooves in registry with the grooves in the grinding wheel and within which the edges of the glass sheets are adapted to be received, fixed guide brackets mounted at opposite sides of the work holder and having vertical guideways therein, means carried by the side members of said work holder and slidably received within said guideways, said last-mentioned means being of such construction as to cause rocking movement of the work holder relative to said guide brackets, and means for rocking the said work holder to move the curved edges of the sheets over and in engagement with the grinding wheel.

13. In a machine for simultaneously grinding the curved edges of a plurality of glass sheets or plates, a rotary grinding wheel positioned to rotate about a substantially horizontal axis and having a plurality of grooves formed in the periphery thereof, means for supporting the glass sheets to be ground on edge in a substantially vertical position including a holder arranged above said grinding wheel and comprising spaced vertical side members between which said sheets are received and a plurality of horizontal rollers carried by and arranged between said side members for maintaining the glass sheets in position during grinding, said rollers being provided with grooves in registry with the grooves in the grinding wheel and within which the edges of the glass sheets are adapted to be received, fixed guide brackets mounted at opposite sides of the work holder and having vertical guideways therein, blocks slidably mounted in said guideways, horizontal trunnions carried by the side members of the work holder and loosely received within said blocks defining a horizontal axis about which the said work holder is adapted to be rocked, and means for rocking the work holder to move the curved edges of the sheets over and in engagement with the grinding wheel, said last-mentioned means including substantially horizontal connecting rods pivotally mounted at their inner ends to opposite sides of said work holder, and means for reciprocating said connecting rods including a motor and operative drive connections between said motor and said rods.

14. In a machine for simultaneously grinding the curved edges of a plurality of glass sheets or plates, a rotary grinding wheel positioned to rotate about a substantially horizontal axis, a work holder arranged above said wheel and adapted to support the glass sheets to be ground on edge in a substantially vertical position, said work holder including spaced vertical side members between which said sheets are received and means carried by and arranged between said side members for maintaining the said sheets in position during grinding, means for pivotally mounting the work holder about its pivot to move the curved edges of the sheets over and in engagement with the grinding wheel, means for guidingly supporting the said work holder for free vertical movement during the rocking thereof, said rocking means including substantially horizontal connecting rods pivotally mounted at their inner ends to opposite sides of the work holder, and means for reciprocating said connecting rods

including a motor and operative drive connections between said motor and said rods.

15. In a machine for simultaneously grinding the curved edges of a plurality of glass sheets or plates, a rotary grinding wheel positioned to rotate about a substantially horizontal axis and having a plurality of grooves formed in the periphery thereof, means for supporting the glass sheets to be ground on edge in a substantially vertical position including a holder arranged above said grinding wheel and comprising spaced vertical side members between which said sheets are received and a plurality of horizontal rollers carried by and arranged between said side members for maintaining the glass sheets in position during grinding, said rollers being provided with grooves in registry with the grooves in the grinding wheel and within which the edges of the glass sheets are adapted to be received, fixed guide brackets mounted at opposite sides of the work holder and having vertical guideways therein, blocks slidably mounted in said guideways, horizontal trunnions carried by the side members of the work holder and loosely received within said blocks defining a horizontal axis about which the said work holder is adapted to be rocked, and means for rocking the work holder to move the curved edges of the sheets over and in engagement with the grinding wheel, said last-mentioned means including substantially horizontal connecting rods pivotally mounted at their inner ends to opposite sides of said work holder, and means for reciprocating said connecting rods including a motor and operative drive connections between said motor and said rods.

16. In a machine for simultaneously grinding the curved edges of a plurality of glass sheets or plates, a rotary grinding wheel positioned to rotate about a substantially horizontal axis, a work holder arranged above said wheel and adapted to support the glass sheets to be ground on edge in a substantially vertical position, said work holder including spaced vertical side members between which said sheets are received and means carried by and arranged between said side members for maintaining the said sheets in position during grinding, means for pivotally mounting the work holder about its pivot to move the curved edges of the sheets over and in engagement with the grinding wheel, means for guidingly supporting the said work holder for free vertical movement during the rocking thereof, said rocking means including substantially horizontal connecting rods pivotally mounted at their inner ends to opposite sides of the work holder, means for reciprocating said connecting rods including a motor and operative drive connections between said motor and said rods, and means engageable by the work holder at the completion of the grinding cycle for raising said work holder to lift the glass sheets out of engagement with the grinding wheel.

17. In a machine for simultaneously grinding the curved edges of a plurality of glass sheets or plates, a rotary grinding wheel positioned to rotate about a substantially horizontal axis and having a plurality of grooves formed in the periphery thereof, means for supporting the glass sheets to be ground on edge in a substantially vertical position including a holder arranged above said grinding wheel and comprising spaced vertical side members between which said sheets are received and a plurality of horizontal rollers carried by and arranged between said side members for maintaining the glass sheets in position

- 5 during grinding, said rollers being provided with 5
grooves in registry with the grooves in the grinding
wheel and within which the edges of the
glass sheets are adapted to be received, fixed
5 guide brackets mounted at opposite sides of the
work holder and having vertical guideways there-
in, blocks slidably mounted in said guideways,
horizontal trunnions carried by the side members of
the work holder and loosely received within
10 said blocks defining a horizontal axis about which
the said work holder is adapted to be rocked,
means for rocking the work holder to move the
curved edges of the sheets over and in engage-
ment with the grinding wheel, said last-men-
15 tioned means including substantially horizontal
connecting rods pivotally mounted at their inner
ends to opposite sides of said work holder, means
for reciprocating said connecting rods including
a motor and operative drive connections between
20 said motor and said rods, and means engageable
by the work holder at the completion of the
grinding cycle for raising said work holder to
lift the glass sheets out of engagement with the
grinding wheel.
25 18. In a machine for simultaneously grinding
the curved edges of a plurality of glass sheets or
plates, a rotary grinding wheel positioned to ro-
tate about a substantially horizontal axis, a
work holder arranged above said wheel and
30 adapted to support the glass sheets to be ground
on edge in a substantially vertical position, said
work holder including spaced vertical side mem-
bers between which said sheets are received and
means carried by and arranged between said side
35 members for maintaining the said sheets in po-
sition during grinding, fixed guide brackets
mounted at opposite sides of the work holder
and having vertical guideways therein, means
carried by the side members of said work holder
40 and slidably received within said guideways, said
last-mentioned means being constructed to cause
rocking movement of the work holder relative
to said guide brackets, means for rocking the
said work holder to move the curved edges of
the sheets over and in engagement with the
grinding wheel, said rocking means including a
motor and operative drive connections between
the motor and work holder, and means actuated
by said work holder at the completion of the
grinding cycle to automatically shut off said
motor and bring the work holder to a stop.
10 19. In a machine for simultaneously grinding
the curved edges of a plurality of glass sheets
or plates, a rotary grinding wheel positioned to
rotate about a substantially horizontal axis, a
work holder arranged above said wheel and
15 adapted to support the glass sheets to be ground
on edge in a substantially vertical position, said
work holder including spaced vertical side mem-
bers between which said sheets are received and
means carried by and arranged between said side
20 members for maintaining the said sheets in po-
sition during grinding, fixed guide brackets
mounted at opposite sides of the work holder
and having vertical guideways therein, said
last-mentioned means being constructed to cause
25 rocking movement of the work holder relative
to said guide brackets, means for rocking the
said work holder to move the curved edges of
the sheets over and in engagement with the
grinding wheel, said rocking means including a
30 motor and operative drive connections between
the motor and work holder, and means actuated
by said work holder at the completion of the
grinding cycle to automatically shut off said
motor and bring the work holder to a stop, and
35 means engageable by the work holder at the comple-
tion of the grinding cycle for raising said work
holder to lift the glass sheets out of engagement
with the grinding wheel.
